TERMINAL CLAMP

John C. Krueger, Port Angeles, Wash., assignor
of one-half to Charles W. Greenlee, Port
Angeles, Wash.

Application August 23, 1932. Serial No. 630,097

1. Claim. (Cl. 173—259)

This invention relates to battery terminal clamps, and its general object is to provide a clamp of the wedge type, that can be associated with a battery post in a manner to set up a positive gripping action, is composed of minimum parts, is simple in construction, inexpensive to manufacture, easy to operate, and extremely efficient in operation and service.

This invention also consists in certain other features of construction and in the combination and arrangement of the several parts, to be hereinafter fully described, illustrated in the accompanying drawing and specifically pointed out in the appended claim.

15 In describing my invention in detail, reference will be had to the accompanying drawing wherein like characters denote like or corresponding parts throughout the several views, and in which:

20 Figure 1 is a fragmentary top plan view illustrating the application of my clamp to a battery post.

Figure 2 is a sectional view taken approximately on line 2—2 of Figure 1.

25 Figure 3 is a bottom plan view of one section of my clamp.

Figure 4 is a perspective view of the wedge section thereof.

Figure 5 is a side elevation of the clamp.

30 Figure 6 is a top plan view illustrating a slightly modified form.

Referring to the drawing in detail, the letter A indicates a battery that is provided with the usual post B adapted to receive the clamp 35 which forms the subject matter of the present invention.

It will be noted that the clamp is made up of two sections, one of which is clearly shown in Figure 3 and includes a body 1 having formed 40 with one end a cable sleeve 2 that is disposed at right angles with respect to the body, and the opposite end of the body has formed therewith a post collar 3 which of course is adapted to receive the post B as clearly shown in Figure 2.

45 The body is provided with a channel made up of side walls and an inclined wall that terminates at one end into the post collar and merges in close proximity to the cable sleeve at its opposite end. The body is provided with an oblong bore 4 that extends through the inclined wall and the upper end of the body as best shown in Figure 2.

Cooperating with the channel and particularly with the inclined wall thereof is a wedge 5 having an inclined wall 6 substantially co-exten-

sive and engageable with the inclined wall of the channel, and the wedge 5 is provided with a grooved face 7 curved to follow the curvature of the post B for engagement therewith as will be apparent. It will be further noted that the wedge 5 is provided with a threaded bore 8 for the purpose of threadedly receiving the threaded shank of a screw bolt 9. The shank passes through the oblong bore 4 and is movable longitudinally thereof to move the wedge accordingly and in the direction of the post so as to set up a gripping action between the post, post collar and wedge when the screw bolt is screwed downwardly into the threaded bore 8, as will be apparent.

In Figure 6 I have illustrated a slightly modified form of the invention and which shows the cable sleeve arranged in alignment with the body 1. Otherwise the structure is similar to that disclosed in the remaining figures of the drawing.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:

A battery terminal clamp comprising a body 85 provided with a channel including side walls and an inclined wall, a cable sleeve formed with one end of said body, a battery post collar formed with the opposite end thereof, said inclined wall extending the entire depth of the channel and 90 terminates at one end in close proximity to the post collar and merges into the cable sleeve at its opposite end said body having an oblong bore arranged in the inclined wall, a wedge provided with an inclined wall mounted for slidable movement on the inclined wall of the channel and being substantially coextensive therewith, said wedge being provided with a threaded bore, a screw bolt having its shank extending through the oblong bore and threadedly received in the 95 threaded bore for moving the wedge in gripping engagement with a battery post, and said wedge being provided with a rounded groove engageable with said post and following the curvature thereof.

JOHN C. KRUEGER.
